UNITED STATES PATENT OFFICE

EDWARD A. CONNER, OF STRATFORD, CONNECTICUT, ASSIGNOR TO AMERICAN CABLE COMPANY, INC., A CORPORATION OF DELAWARE

MACHINE FOR MAKING WIRE STRANDS, ROPES, AND CABLES

Application filed January 12, 1927, Serial No. 180,571. Renewed February 11, 1930.

This invention relates to the manufacture of wire strand, rope or cable, and more particularly to the formation of an article of this class in which a helical conformation is imparted to the several components preparatory to laying the components in the strand, rope or cable, so that the article produced will have inert lay characteristics, i. e., will be free from tendency to separation of the components when the strand, rope or cable is cut, and will also be free from tendency to kink, the components of such an inert lay article preserving throughout the life of the article a compact formation which increases its working life and insures the desirable qualities of flexibility and smooth running when in operation upon the drums or grooved pulleys conventionally employed in connection with elevators and in other installations where power is to be transmitted by the strand, rope or cable.

For the sake of brevity in description, the product will be hereinafter referred to as "strand" but it is to be understood that this expression is used inclusively to designate not only strand in the technical sense of an article composed of several wires, but also to designate a rope composed of several strands or a cable composed of several ropes each having a plurality of component strands.

An important object of the invention is to provide an improved process of imparting to the strand components a helical conformation preparatory to laying them to constitute the complete strand, rope or cable, by subjecting the components to the action of dies or preforming devices which are given a rotary movement for the purpose of forming the components helically, the rotative movement of the dies also serving preferably to feed the components severally with a rotative movement around the axes of the helices thus formed, and preferably also acting to lay the helical components simultaneously in proper relative position to form the completed strand, rope or cable having the inert lay characteristics to which reference has already been made.

Another object of the invention is to pro-

vide a machine organized to carry the aforesaid process into effect and adapted to form continuously inert lay strand, rope or cable automatically and economically for commercial use.

These and other objects of the invention are illustrated and described fully in the accompanying drawings and specification and are pointed out in the claims, with particular reference to a now preferred embodiment of the invention.

In the drawings—

Fig. 1 is a view in side elevation of apparatus adapted to carry the process into effect.

Fig. 2 is a detail view in vertical, longitudinal section, on an enlarged scale, of part of the apparatus shown in Fig. 1.

Fig. 3 is a vertical section on the line 3—3 of Fig. 2.

Fig. 4 is a detail view in side elevation, partly in section, of one of the preforming dies, with associated parts.

Fig. 5 is a similar view of one of the dies showing also wire preformed thereby.

Figs. 6 and 7 show modifications of the preforming devices.

In the embodiment illustrated, the apparatus comprises a preforming head, designated generally by the reference character A, which imparts the desired helical conformation to strand components 1, derived from supply reels 2 and 2^a, carried by a rotatable frame which is designated generally by the reference character B, the preforming head delivering the helically formed components to a closing die C from which the completed strand, rope or cable P proceeds to a drawing-off unit D.

In the instance selected for illustration and description, six of the components 1 are being preformed simultaneously and laid about a core 3 which is derived from a suitable supply, not shown, the core being led through a hollow rotatable spindle 4, upon which are mounted the frame B of supply reels and the preforming head A, so that the head and frame rotate with the spindle, the latter being journaled in suitable bearing standards 5 and 6 extending from a base 7, suitable change-speed gearing being provided, as in-

dicated at 8, to permit the spindle to be driven at the desired speed by a shaft 9 actuated from a suitable source of power not shown.

5 In pursuance of the invention, the pre-forming head A is provided with a series of pre-forming devices 10 each adapted to operate upon a strand component 1, and these devices are desirably mounted in spaced relation around the main axis of the apparatus, represented by the core 3, and are adapted to be rotated individually each about its own axis, while each revolves about the core 3. Any suitable structure may be provided to 10 effect these movements of rotation and revolution, and as a convenient form of construction for this purpose, a hollow extension shaft 11 is shown, connected at 12 with the spindle 4 so as to rotate therewith, and having a collar 13 secured to the spindle by a set screw 14, and furnished with a flange 15, of frusto-conical shape, in which are bearings to receive a series of sleeves 16, one for 15 each of the pre-forming devices 10 (see Figs. 2 and 4).

20 To provide for rotation of the devices 10, each about its own axis, the sleeves 16 are connected by universal joints 17 with short shafts 18 mounted in bearings 19 carried by a plate 20 secured removably, as by screws 21, to the face of a hub 22 which is keyed at 23 to the spindle 4 and is rotated thereby. This hub is recessed at 24 to receive spur-gears 25, keyed at 26 to the short shafts 18, 25 and these gears mesh with pinions 27 upon shafts 28 also mounted in bearings at 29 in the hub between the spur gears 25, and the shafts 28 are furnished with gears 30 adapted to mesh with an interior ring gear 31, the latter being supported by a ring 32, 30 mounted on the standard 6, being held in place by brackets 34 through which extend set-screws 35. Other set-screws 33 serve to prevent accidental displacement of the ring gear 31 from its supporting ring 32 when removed from the supporting standard, but permit removal of the ring gear readily when it is desired to inspect the hub or change the gears.

35 50 By providing a ring gear 31 and spur gears 30 of proper ratio, any desired speed of rotation of the devices 10 relatively to their speed of revolution about the spindle 4 may be provided for, and it will be understood readily from the above description that when the spindle 4 rotates, the gears 30 track or run around within the fixed ring 31, turning the shafts 28 and pinions 27 which act to turn the spur gears 25, shafts 18, universal joints 17 and pre-forming devices 10, in unison.

55 The pre-forming devices 10 may be of any construction suitable to effect the desirable helical conformation of the strand components 1, and in the instance illustrated the devices 10 are constituted as dies having hel-

ical peripheral grooves 40 closed by the inner walls 36 of the sleeves 16, the latter serving to confine the strand components 1, so that as the sleeves 16 and dies 10 are rotated, they co-operate to form the strand components I 70 helically, and at the same time to feed the same forward into position to lay them around the core 3 in proper relative position to constitute the finished product P. The helical conformation of the components is indicated at 41 in Fig. 5, at the region where they emerge from the pre-forming devices, the latter having heads 37 (see Fig. 4) adapted to assist in turning out the components after they have been thus preformed helically. The pre-forming devices 10 are preferably disposed diagonally toward the core 3, and arranged as closely as possible in juxtaposition thereto, so as to deliver the helical components in close relation to each other 85 adjacent to the closing die C.

90 After passing through the closing die, the finished product P may be drawn off and accumulated upon any suitable reel, not shown, the drawing off mechanism illustrated comprising a pair of drums 38 around each of which the product P may be given one or more turns, the drums being preferably connected by a belt 39, one of the drums being driven by a shaft 42 geared at 43 to the lay shaft 9, so that the drawing off mechanism 95 has its speed co-ordinated with the speed of formation of the product P.

100 As already indicated, briefly, the supply unit B may be of any suitable construction to serve for supplying the individual strand components to the pre-forming devices, and as a convenient form of construction for this purpose I have shown a supply frame of the character illustrated and described in my United States Letters Patent No. 1,518,253 to which reference may be had for a complete description it being sufficient to note that the frame has a rotatable end 44 with a sleeve bearing 45 mounted within the standard 6 (see Fig. 2), surrounding the hollow shaft 4 and keyed thereto at 46, and preferably having a plate 47 secured by screws 48 in such a manner as to hold the sleeve 45 against longitudinal movement.

115 The frame has arms 49 provided at their ends with rollers 50 running in a circular track 51 which aids to sustain the strains resulting from centrifugal force upon the arms 49, and each arm is provided with suitable pulleys 52 over which the strand components 1 are led respectively from the supply reels 2, the latter being mounted co-axially upon the spindle 4. Reels like those shown at 2^a 120 may be utilized as reserve reels, being placed upon the spindle between each two of the main supply reels 2, in the manner described in my aforesaid Letters Patent, and in order to remove and replace the reels, the spindle 4 may be removed from the bearing stand- 125 130

ard 6 sufficiently in a lengthwise direction, to permit one or more of the reels to be slipped off the spindle 4. A collar 53 with set screw 54 may be provided to hold the reels in their normal position as illustrated.

5 In operation, after full supply reels 2 have been placed upon the spindle 4, with or without the reserve reels 2^a, and the strand components 1 have been led over the pulleys 52, and through the apertures 55 of the preforming head, thence through the peripheral grooves 40 in the preforming dies and into the closing die C, the machine is started, and the rotative action of the dies 10 upon the 10 strand components forms them individually in a helical manner and at the same time causes rotation of the helical components thus formed and their advance into position to be laid in the finished product P, the revolution 15 of the head completing the laying operation, and the closing die C insuring uniformity of the product, the latter being drawn off by the mechanism D already described.

20 25 It is to be observed as already noted that any desired and suitable ratio between the number of turns in the revolution of the head A and the simultaneous number of rotative turns of each of the preforming devices 10 may be secured by provision of gears 30 and a ring gear 31 having the necessary relative numbers of teeth. An important object of providing for such changes of gearing is to provide desirable means for compensating 30 for the differing elastic co-efficient existing in the high carbon steel wires which constitute ordinarily the strand components, in modern usage, it being found desirable in practice to cause the preforming devices 10 to rotate in 35 a forward direction as they revolve and extrude the helical components. By this provision a slight excess of "set" is imparted to each helical component over that required to form a helix of given radius and thus is 40 avoided any tendency on the part of the respective helical components to separate after having been laid in the strand, rope or cable.

45 In Figs. 6 and 7 I have shown modifications of the preforming devices, which may be used in a planetary head in place of the formation of preforming device illustrated in Figs. 1 to 5 inclusive.

50 The modification shown in Fig. 6 comprises a frame 64 having a shank 65 corresponding to the shank 18 or short shaft of the device illustrated in Fig. 4, the frame being provided with two sets of rolls 62 and 63 respectively between which the wire 1 to be preformed is extended after passing through 55 the whole shaft 65. The wire is then subjected to the action of a roll 67 mounted in a fork 68 carried by an adjustable screw 69 extending from a lug 70 upon the forward 60 end of the frame, and when the frame is 65 rotated by the action of the planetary gearing

hereinbefore described, a helical formation is imparted to the wire 71, it being understood that the same structure is adapted to operate upon wire strand or rope as well as upon individual wires.

70 In the modification shown in Fig. 7, a frame 58 is mounted upon a short shaft 59 adapted for use in place of the short shaft 18 shown in Fig. 4, and a wire 61 is led through a set of rolls 56 mounted as shown in Fig. 7, the wire passing under the first and third of the series and over the intervening roll in the manner shown in Fig. 7. The wire when it issues from the forward end of the device shown in Fig. 7 has the helical formation of the wire shown at 41 in Fig. 5. This modification also may be used for preforming wire strand or rope in the place of the preforming device illustrated in Figs. 1 to 4 inclusive.

75 80 Certain of the features herein disclosed form the subject-matter of my divisional application Ser. No. 239,186, filed December 10, 1927, and the right to prosecution of subject-matter not claimed herein is expressly reserved.

85 I claim:

90 1. In a machine for making wire strand, rope or cable, a preforming head comprising a central shaft having a member rotatable therewith and furnished with a plurality of preforming devices mounted for individual rotation in bearings spaced around the axis of said central shaft, and a hub on said central shaft having planetary gearing adapted to rotate said preforming devices individually.

95 100 105 2. In a machine for making wire strand, rope or cable, a preforming head comprising a central shaft having a member rotatable therewith and furnished with a plurality of preforming devices mounted for individual rotation in bearings spaced around the axis of said central shaft, and a hub on said central shaft having planetary gearing adapted to rotate said preforming devices individually, gearing adapted to drive said planetary gearing, a support for said central shaft and said drive gearing and means to cause relative rotation between said central shaft and drive gearing.

110 115 120 125 3. In a machine for making wire strand, rope or cable, a preforming head comprising a central shaft having a member rotatable therewith and furnished with a plurality of preforming dies mounted for individual rotation in bearings spaced around the axis of said central shaft, a hub on said central shaft having planetary gearing adapted to rotate said preforming dies individually, a ring gear adapted to actuate said planetary gearing, a support for said central shaft and said ring gear, and means to cause relative rotation between said central shaft and ring gear.

130 4. In a machine for making wire strand, rope or cable, a preforming head comprising

- a central shaft having a member rotatable therewith and furnished with a plurality of preforming dies mounted for individual rotation in bearings spaced around the axis of said central shaft, a hub on said central shaft having planetary gearing adapted to rotate said preforming dies individually, a ring gear adapted to actuate said planetary gearing, a support for said central shaft and said ring gear, and means to rotate said central shaft relatively to said ring gear. 75
5. In a machine for making wire strand, rope or cable, a preforming head comprising a central shaft having a member rotatable therewith and furnished with a plurality of preforming dies mounted for individual rotation in bearings spaced around the axis of said central shaft, a hub on said central shaft having planetary gearing adapted to rotate said preforming dies individually, a ring gear adapted to actuate said planetary gearing, a support for said central shaft and said ring gear, and means to cause relative rotation between said central shaft and ring gear, 80
- 10 means to support said dies in converging position, and connections between said dies and planetary gearing. 85
- 15 6. In a machine for making wire strand, rope or cable, a preforming head comprising a central shaft having a member rotatable therewith and furnished with a plurality of preforming dies mounted for individual rotation in bearings spaced around the axis of said central shaft, a hub on said central shaft having planetary gearing adapted to rotate said preforming dies individually, a ring gear adapted to actuate said planetary gearing, a support for said central shaft and said ring gear, and means to cause relative rotation 90
- 20 between said central shaft and ring gear, means to support said dies in converging position, and connections between said dies and planetary gearing, said connections comprising a series of pinion-shafts actuated 95
- 25 by said series of planetary gears, and a series of shafts provided with universal joints connected operatively with said converging dies and having gears operated by said pinion-shafts. 100
- 30 7. In a machine for making wire strand, rope or cable, a preforming head comprising a central shaft having a member rotatable therewith and furnished with a plurality of preforming dies mounted for individual rotation in bearings spaced around the axis of said central shaft, a hub on said central shaft having planetary gearing adapted to rotate said preforming dies individually, a ring gear adapted to actuate said planetary gearing, a support for said central shaft and said ring gear, and means to cause relative rotation 105
- 35 between said central shaft and ring gear, said means comprising a rotatable spindle 110
- 40 provided with supply reels for the strand. 115
